UNITED STATES PATENT OFFICE.

FREDERIC AUMONIER, OF LONDON, ENGLAND.

DESIGN FOR WALL OR CEILING PAPER.

SPECIFICATION forming part of Design No. 23,116, dated March 13, 1894.

Application filed February 9, 1894. Serial No. 499,690. Term of patent 3½ years. Registered in England March 3, 1893, No. 208,522.

To all whom it may concern:

Be it known that I, FREDERIC AUMONIER (trading as Wm. WOOLLAMS & Co.,) a subject of the Queen of Great Britain, and a resident of 110 High Street, near Manchester Square, London, England, have invented a new and original Design for Wall or Ceiling Paper, (registered in Great Britain on the 3d of March, 1893, No. 208,522,) of which the following is a specification.

The design for wall and ceiling paper is represented on the accompanying drawing and consists of a square tablet outside of which are four oblong like devices and inter-
mixed with four corners composed of seg-
ments of circles from the curves of which the

said oblongs are connected by circles and bars. The central square is partitioned in an ornamental manner and the intermediate spaces are filled with conventional leaves, scrolls and flowers as indicated.

I claim—

The design for wall and ceiling paper substantially as herein shown and described.

The 10th day of March, 1893.

FREDERIC AUMONIER.
